MATRIX LATCHING DEVICE

Arnold Duerksen, Lodi, Calif., assignor to Super Mold Corporation of California, Lodi, Calif., a corporation of California

Application December 14, 1953, Serial No. 397,953

13 Claims. (Cl. 18—38)

This invention relates to a tire treading or vulcanizing mold, and particularly to one of the type which includes separate cooperating matrix halves or sections and platens or body members on which the matrix halves are mounted, and which body members are connected to a mechanism to move the same toward and from each other to correspondingly shift the matrix sections from closed to open positions.

The matrix sections are heated when in operation and are not permanently secured to the platens in order to enable the latter to be used, without change, with matrix sections of different diameters or widths.

It is, therefore, necessary to provide means to detachably secure the matrix sections, irrespective of their size, onto the platens; and one object of the present invention is to provide a means for quickly and easily securing such variable size matrix sections in place on the platens.

Each matrix section includes a radial outwardly projecting flange, and the securing or latching means includes a hook-like latch member mounted on the platen to overhang and clamp the flange against movement.

Since the matrix is heated, allowance must be made for the accompanying expansion as otherwise fracturing or distortion is liable to occur. A further object of the invention, therefore, is to provide means whereby the latch member may yield outwardly with expansion of the matrix section, while, at the same time, always holding the matrix section firmly seated on the platen.

The latching means includes a rotatable hand-actuated control member whose rotation in one direction advances the latch member into a flange clamping position, and another object of the invention is to arrange said control member so that the advancing pressure which may be exerted on the latch member is limited to a predetermined amount, regardless of the strength of the operator or the leverage which he may impart to the control member. In this manner, it is impossible to clamp the matrix flange with a pressure of such severity as would prevent the desired radially outwardly movement of the latch member as the matrix expands.

Still another object of the invention is to provide a matrix latching device which is practical, reliable, and durable, and one which is exceedingly effective for the purpose for which it is designed.

These objects are accomplished by means of such structure and relative arrangement of parts as will fully appear by a perusal of the following specification and claims.

In the drawings:

Fig. 1 is a top plan view of a matrix section as mounted on a mold platen and removably clamped in place by the improved clamping units.

Fig. 2 is an enlarged cross section on line 2—2 of Fig. 1.

Fig. 3 is a transverse section on line 3—3 of Fig. 2.

Referring now more particularly to the characters of reference on the drawings, the platen or mold structure for each matrix section includes a substantially circular

2

ring-like body member 1 having a flat plate 2 secured on one face thereof and forming the matrix-section supporting area of the body member.

5 A matrix half or section 3 rests on plate 2; this section, as here shown, being of the electrically heated type.

The matrix section 3, which is of ring-like form, is centered on the plate 2 so as to be concentric therewith either by directly engaging a stop bead 4 upstanding from plate 2 at the radially inner end thereof, or, as here shown, by engaging a spacer band 5 seated on the plate and which, in turn, engages bead 4.

15 The radial extent of the plate 2 is such as to support matrix sections of different diameters thereon. The matrix section of whatever diameter, however, includes an outwardly exposed base flange 6 whose upper surface slopes in a direction from its outer edge so that said flange 6 is wedge-shaped in section, as shown in Fig. 2.

A number of the yieldable clamping devices 7 for the matrix section, and which form the subject matter of this invention, are mounted on the body 1 in circumferentially spaced relation, as shown in Fig. 1; said body being formed with a radially extending, depressed recess or socket 8 below plate 2 and extending outwardly therefrom for each such device 7.

20 Each device 7 comprises a shaft 9 extending radially of the body 1 within the socket 8 and journaled intermediate its ends, for rotary and limited axial movement in the outer cross member 10 of the socket, and in an intermediate cross web 11 in the socket.

25 Between members 10 and 11, the shaft is formed with threads 12 on which a flange engaging and clamping member 13 is mounted. This member comprises a boss 14 threaded on threads 12; a shank 15 projecting from the boss through and guided by a radially extending slot 16 in plate 2, and a hook 17 on the outer end of the shank clear of the plate 2 to engage over the flange 6.

30 The under surface of hook 17 has the same slope as said flange so that as the member 13 is advanced, the hook will gradually engage and press the flange 6 down onto the plate 2. The slot 16 allows movement of the member 13 radially of the matrix and plate while preventing rotation thereof about shaft 9.

35 Rearwardly of and spaced from web 11, another web 18 is formed across socket 8 through which the inner end portion 19 of shaft 9 projects, and on which a sleeve 20 is held against axial movement relative to the shaft; said sleeve including an outwardly projecting flange 21 bearing against the outer face of web 18.

40 A heavy compression spring 22 surrounds the spring between web 11 and flange 21, and resists outward axial movement of the shaft 9 from its normal position.

45 By reason of the above structure and arrangement of parts, it will be seen that any radially outward movement of matrix flange 6 (occasioned by expansion of the matrix due to heat, and after the hook 17 has been closely engaged with said flange) will cause the spring 22 to be compressed, thus allowing the shaft 9 and hook member 13 to move radially out as a unit without disturbing the desired hold-down action of the hook member on the matrix section.

50 The shaft 9 is rotated by hand to advance the hook member into clamping engagement with the matrix flange 6. In order that excessive rotative pressure cannot be exerted on the shaft, and which would be sufficient to cause the spring 22 to be compressed and the shaft moved outwardly after the hook member has properly engaged the matrix flange, a special control or shaft manipulating device is provided.

55 This device comprises a sleeve 23 non-turnably mounted on the outer end portion 24 of shaft 9, and which sleeve is turnably mounted in the hub 25 of a hollow

radially projecting arm 26 which, at its outer end, is fitted with a crank handle 27.

A plunger 28 is slideable in the arm 26 and is formed on its outer end with a cross rib or key 29 engaging a longitudinal external slot 30 in the sleeve 23. The side of the key which faces in the direction of rotation of the sleeve and shaft necessary to advance the clamping member 7 is cut on a slope as is the slot 30, as shown at 31 in Fig. 3.

A compression spring 32, whose load or pressure is determined by adjustment of a screw plug 33, is disposed in the arm 26 to yieldably press the plunger against the sleeve 23.

A pin 34 projects from the plunger and rides in a longitudinal slot 35 in the arm 26 so as to prevent rotation of the plunger if and when the key 29 becomes disengaged from the slot 30.

The spring 32 is set by adjustment of plug 33 so that its resistance is such that when the member 13 has been advanced, by rotation of shaft 9, into the desired clamping engagement with the matrix flange 6, the spring 32 will yield and cause the plunger to move away from sleeve 23 and thus disengage the key 29 from slot 30 before any compression of the spring 22 takes place, and also, of course, before any excessive clamping action of the member 13 against the matrix flange is had.

This release of the key from its slot is made possible by reason of the taper or slope 31 of the key and slot. When the member 13 is prevented from further advance by its engagement with the flange 6, further rotations of the handle 27 and arm unit 26 may take place without any rotation being imparted to the sleeve 23 or shaft 9; the key 29 merely clicking in and out of the slot with repeated rotations of the unit.

The structure here shown and described takes care of one half of a complete mold structure; the other co-operating half being substantially a duplicate of said one half, but, of course, arranged in inverted relation thereto.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired.

1. In a tire mold having a matrix supporting plate, a circular matrix section removably seated on the plate, and a plurality of devices mounted on the mold and spaced circumferentially of the matrix section to clamp the matrix section to the plate; each such device comprising a rotatable shaft mounted on the mold adjacent the plates radially of the matrix section, a portion of the shaft being threaded, a member mounted on said threaded portion for advance along the same upon rotation of the shaft, said member projecting through a slot in the plate and including an element to overhang and engage a peripheral flange on the matrix section, the shaft at its outer end being arranged for manual rotation, means journaling the shaft on the mold for rotation and limited axial movement, and means between the shaft and mold and including a spring to yieldably resist outward movement of the shaft.

2. A device as in claim 1, in which said last named means comprises longitudinally spaced relatively inner and outer transverse webs on the body through which the shaft projects beyond the end of the threaded portion thereof, a flange fixed on the shaft and normally engaging the outer face of the inner web, and a compression spring about the shaft and extending between said flange and the outer web.

3. A combination, as in claim 1, with hand operated

means to rotate the shaft, including a yieldable connection with the shaft arranged to prevent rotation thereof by said means when resistance to further advance of the shaft-mounted matrix engaging member approaches the yielding point of the shaft-resisting spring.

4. In a tire mold having a matrix supporting plate, a circular matrix section removably seated on the plate, and a plurality of devices mounted on the mold and spaced circumferentially of the matrix section to clamp the matrix section to the plate; each such device comprising a rotatable shaft mounted on the mold adjacent the plate radially of the matrix section, a portion of the shaft being threaded, a member mounted on said threaded portion for advance along the same upon rotation of the shaft, said member projecting through a slot in the plate and including an element to overhang and engage a peripheral flange on the matrix section, and hand operated means to rotate the shaft; said means including a connection with the shaft to prevent rotation of the shaft by said means when resistance to such rotation reaches a predetermined amount.

5. A device, as in claim 4, in which said hand operated means comprises a sleeve non-turnably mounted on the outer end of the shaft, an arm and handle unit turnably embracing the sleeve and extending radially therefrom, and a radially yieldable key connection between the unit and sleeve.

6. A device, as in claim 5, with a spring pressing the key and normally holding the same engaged with the sleeve; the rotatable shaft being mounted on the mold for limited axial movement, and means between the shaft and mold and including a separate spring to yieldably resist outward axial movement of the shaft; said key-pressing spring having a yielding resistance approaching but below that of said separate spring.

7. In a tire mold having a matrix supporting plate, a circular matrix section removably seated on the plate, and a plurality of devices mounted on the mold and spaced circumferentially of the matrix section to secure the matrix section to the plate; each device comprising a rotatable shaft disposed adjacent the plate radially of the matrix section, means journaling the shaft on the mold for rotation and limited axial movement, a portion of the shaft being threaded, a member mounted on said threaded portion for inward advance along the same upon rotation of the shaft, initially separate elements on said matrix section and shaft mounted member adapted for engagement to secure the matrix section to the plate upon such advance of said member along the shaft, means to rotate the shaft, and means between the shaft and mold and including a spring to yieldably resist outward movement of the shaft.

8. A device, as in claim 7, in which said last named means comprises longitudinally spaced relatively inner and outer transverse webs on the body through which the shaft projects beyond the end of the threaded portion thereof, a flange fixed on the shaft and normally engaging the outer face of the inner web, and a compression spring about the shaft and extending between said flange and the outer web.

9. A device, as in claim 7, in which said means to rotate the shaft includes a yieldable connection with the shaft arranged to prevent rotation thereof when resistance to further advance of the shaft-mounted matrix section engaging member approaches the yielding point of the shaft-resisting spring.

10. In a tire mold having a matrix supporting plate, a circular matrix section removably seated on the plate, and a plurality of devices mounted on the mold and spaced circumferentially of the matrix section to secure the matrix section to the plate; each device comprising a rotatable shaft mounted on the mold adjacent the plate radially of the matrix section, a portion of the shaft being threaded, a member mounted on said threaded portion for inward advance along the same upon rotation of the

shaft, initially separate elements on said matrix section and shaft mounted member adapted for engagement to secure the matrix section to the plate upon such advance of said member along the shaft, and means to rotate the shaft; said means including a connection with the shaft to prevent rotation thereof when resistance to such rotation reaches a predetermined amount.

11. A device, as in claim 10, in which said connection comprises a sleeve non-turnably mounted on the outer end of the shaft, an arm and handle unit turnably embracing the sleeve and extending radially therefrom, and a radially yieldable key connection between the unit and sleeve.

12. A device, as in claim 10, with a spring pressing the key and normally holding the same engaged with the sleeve; the rotatable shaft being mounted on the mold for limited axial movement, and means between the shaft and mold and including a separate spring to yieldably resist outward axial movement of the shaft; said key pressing spring having holding resistance approaching but below that of said separate spring.

13. In a tire mold having a matrix supporting plate, a circular matrix section removably engaging the plate, and a plurality of devices mounted on the mold in circumferentially spaced relation adapted to secure the matrix

10

15

20

25

section to the plate; each such device comprising a shaft disposed adjacent the plate radially of the matrix section, means mounting the shaft on the mold for rotation and limited axial movement, means yieldably resisting outward axial movement of the shaft, a portion of the shaft being threaded, a member mounted on said threaded portion of the shaft for inward advance along the same upon rotation of the shaft in one direction, means to prevent rotation of said member without restraining said advance thereof, initially separate elements on said matrix section and shaft mounted member adapted for engagement to secure the matrix section to the plate upon such inward advance of the member, and means to rotate the shaft including a connection operative to release upon predetermined resistance to rotation of the shaft in said one direction relative to the resistance outward axial movement of said shaft.
